LIGHT SHIELD FOR DUPLEX SHADE ROLLERS

Filed May 28, 1927

Witness:

Dr. G. Morris

William G. White Inventor
By Gas 7 Monday Att.

UNITED STATES PATENT OFFICE

WILLIAM E. WHITE, OF CHICAGO, ILLINOIS

LIGHT SHIELD FOR DUPLEX SHADE ROLLERS

Application filed May 28, 1927. Serial No. 195,004.

My invention relates to improvements in devices for use in connection with duplex shade rollers.

In many buildings, such as schools, drafting rooms, etc., it is considered an essential to provide two shade rollers at each window and to mount them at a point midway of the height of the window opening; this in order that light and air may be admitted from the top of the window without interference.

When the shade rollers are mounted in this manner, it inevitably results in an open space between the adjacent rollers through which light is admitted, and this has been overcome in devices heretofore proposed by mounting a shield at such a point that the space between the rollers is closed. However, in each of the devices suggested, the shield has been mounted on the outside of the rollers, that is, adjacent to the window sash. While this accomplishes one result, it exposes the shade rollers and presents difficulties in the mounting, adjustment and operation of the rollers.

One of the objects of my invention is to provide a simple device of the character described and to so arrange the device that it will conceal the shade rollers and at the same time exclude light as required. By forming the shield with a curved cross section and by suitably decorating the exterior of the shield, it may be caused to harmonize and add to the attractiveness of the room.

The invention will be more readily understood by reference to the accompanying drawing, in which;

Fig. 1 is an elevation showing a window frame to which my improvement has been applied;

Fig. 2 is an enlarged side elevation of one of the brackets employed showing the shield in section;

Fig. 3 is an edge view of the bracket, and

Fig. 4 is a plan view of a fragment of the assembly at one end.

In the drawings, a frame 9 is indicated, a pair of brackets of my invention being suitably secured to the inner face thereof. The brackets comprise a body, 10 and a rear right-angled flange, 11. Both the body and the

flange 11 are provided with screw openings in order that the bracket may be secured either to the outer or inner face of the frame as desired. The body of the bracket is provided with shade roller sockets, 12, 13 having suitably shaped apertures to accommodate the round and square ends respectively of the shade rollers.

Formed as an extension of the socket member 13 is a toe or abutment 14 that acts as a bottom stop for the shield. The body 10 of the bracket has inturned tongues 15, 16 offset or staggered as to each other, the space separating the two tongues or ears corresponding substantially to the thickness of the shield element 17. This shield is of generally arcuate form in cross section, and may consist of a thin sheet of metal. The lower edge rests on the toe 14 and the shield is adapted to be positioned by a downwardly sliding movement into the location shown in Fig. 2. For convenience, the shield may be manufactured and sold in long strips and cut to the required length by the dealer.

By locating the shield as shown, the fundamental purpose of excluding light from between the shade rollers is accomplished, and, in addition, the shade rollers, indicated in dotted lines in Fig. 2, are hidden or covered when viewed from the interior of the room. The shield may be painted or calcimined as desired and will not be unsightly. The device is of extreme simplicity and adapts itself to easy installation, removal and replacement.

Modifications may be made in the construction shown without departure from the spirit of my invention, and I do not wish to be limited except as indicated in the appended claims.

I claim:

1. In combination, a bracket and a curved light shield, said bracket having a portion projecting into the room, the marginal edge of the bracket being bent at right angles along a curved line to provide a flange extending throughout the major portion of the bent portion and a tongue offset relative to said flange, the end of said light shield being adapted to be held and concealed by said bent portions.

2. In combination, a bracket and a curved light shield, said bracket having a portion projecting into the room, the marginal edge of the bracket being bent at right angles along a curved line to provide a flange extending throughout the major portion of the bent portion and a tongue offset relative to said flange, the end of said light shield being adapted to be held and concealed by said bent portions, and a stop for said shield, said stop forming a part of said bracket and located inwardly of the body portion thereof.

3. In a window shading means, the combination of a bracket adapted to be permanently secured to a window casing, said bracket having a portion projecting into the room, the margin of which portion is bent in the arc of a circle to provide a holding and covering flange, said bracket also providing means for mounting shade rollers, and a light shield arcuate in cross section an end of which is adapted to be slid into holding engagement with the flange of said bracket.

In testimony whereof I have affixed my signature.

WILLIAM E. WHITE.
